UNITED STATES PATENT OFFICE

CHESTER H. BRASELTON, OF NEW YORK, AND FRED B. MACLAREN, OF MALBA, NEW YORK

INERTIA PUMP

Application filed January 30, 1922, Serial No. 532,718. Renewed September 14, 1928.

The present invention relates to vibration operated pumps for pumping fluids from a source of supply to a desired destination by utilizing the relative vibration of the pump plunger and pump cylinder to effect the pumping action. A pumping apparatus of this type is disclosed in our copending application bearing Serial No. 531,137, filed January 23, 1922, and this invention is a modified form of the invention disclosed in this co-pending application.

The principal object of the invention is to provide a means for dampening the relative vibrations between the movable members of the pumping mechanism by trapping the pump with liquid in a chamber and providing a restricted outlet therefor which forms substantially a liquid seal for the fluid being pumped to control or modify the pumping action.

The invention in the embodiment disclosed makes use of a loose piston fitting in a cylinder and means whereby relative movement between the piston and cylinder is produced by the vibration of the latter, the piston and cylinder cooperating through valve mechanism to pump a fluid or liquid from one receptacle to another.

The invention in the embodiment disclosed also relates to means to prevent flow after a certain amount of liquid has been pumped into an auxiliary tank, and to this end means for dampening the relative oscillation between the piston and cylinder dependent upon the height of liquid pumped in the receiving tank are utilized in the present disclosure. The present invention also includes means to regulate, dampen or control extreme vibrations of the pumping mechanism employed.

Another object of the invention is to provide means working in cooperation with the supply pipe to the pump whereby a more continuous flow of liquid to the pump is provided, a small reservoir of the liquid being provided adjacent the supply pipe and in communication therewith which is intermittently under greater or less pressure and tends to act as a governor to provide a

smoother and more continuous flow of liquid through the supply pipe to the pump.

Other objects of the invention are to produce a cheaper and more efficient pumping mechanism and one which is more improved in operation as will more fully hereinafter appear from a detailed description of the construction and relationship of the various parts, as shown in the accompanying drawings in which,

Figure I shows in a conventional manner an automobile with our invention applied thereto for the purpose of pumping liquid fuel from a lower supply tank to a higher level auxiliary tank.

Figure II is a vertical sectional view through the pumping mechanism shown in Figure I.

Figure III is an enlarged view of the central part of Figure II, showing the valves of the pumping mechanism.

In Figure I, 1 represents the automobile shown in a conventional manner supplied with a rear fuel supply tank 2, and a carburetor 3 for the engine 4. An auxiliary pumping tank 5 is shown located on the dash 6 of the automobile and this pumping tank is connected through supply pipe 7 with the rear tank and through outlet pipe 8 to supply fuel to the carburetor.

The object of our invention as herein applied is to cheaply and efficiently keep the pump tank 5 supplied at a proper level with liquid fuel pumped from the rear tank 2 so that the fuel may flow by gravity from the auxiliary tank 5 to the carburetor as needed. To this end the pumping tank 5 is mounted rigidly upon the dash or it may be mounted on any other vibrating part of the automobile or engine so that as the car is moved over the roads or the engine is vibrating due to its operation, or any mechanical means vibrates the pump tank 5 the same will cause the mechanism, due to a floating piston and cooperating cylinder in the pump tank, to pump liquid fuel into the receiving chamber of the pump tank from the rear tank until it is sufficiently full.

The present invention is an improvement upon the inventions disclosed and claimed

in our co-pending applications for Letters Patent, Serial No. 533,493, filed February 1, 1922, fuel supply system for automotive vehicles, and Serial No. 531,137, filed January 5 23, 1922, fuel supply system for automotive vehicles. In the said applications, we have disclosed a fuel supply system for automobiles in which liquid fuel is pumped from a low level supply tank to an auxiliary tank by an 10 inertia-operated pumping mechanism operated automatically by the vibrations normally inherent in the automobile when it is in operation. The liquid fuel is fed by gravity from the auxiliary tank to the carburetor or 15 other charge forming device of the engine and it is important to control the level to which the liquid fuel may rise in the auxiliary tank for the following reasons, among others. It is highly desirable to prevent the auxiliary 20 tank from overflowing, in case liquid is pumped into it faster than it is fed to the engine, because the overflowing of the auxiliary tank would waste the fuel and would spill fuel on the engine with the consequent danger of fire. It is also desirable to control the 25 level to which liquid may rise in the auxiliary tank because such level determines the head or pressure at which the liquid fuel is fed from the auxiliary tank to the carburetor and, if this pressure exceeds a predetermined 30 amount, it is likely to overcome the resistance of the carburetor valve and flood the carburetor. In our application, Serial No. 533,493, we make no attempt to modify or regulate 35 the action of the pumping mechanism and provide an overflow pipe connecting the auxiliary tank and the supply tank and, when the liquid in the auxiliary tank reaches a certain level, the excess flows back to the supply 40 tank through the overflow line. In our application, Serial No. 531,137, we modify the action of the pumping mechanism when the liquid in the tank reaches a certain level. 45 In said application, we accomplish this by providing the inertia-operated piston with an enlarged head which weights the piston and also constitutes a sort of plunger working in the auxiliary tank, so that, when the liquid in the tank reaches such a level that it comes in 50 contact with this enlarged head, the liquid dampens the oscillations of the piston and thus controls or modifies the action of the pumping mechanism. It is to be noted that, in such construction, the liquid is in the path 55 of the discharge stroke of the piston and creates a resistance to the discharge stroke. According to our present invention, we control or modify the action of the pumping mechanism, when the liquid reaches a certain level 60 in the auxiliary tank, by creating a resistance to the intake stroke of the piston. We accomplish this by creating a liquid buffer which opposes the intake stroke of the piston. The construction which we have disclosed for 65 accomplishing this comprises a chamber in

which a part moving with the piston works, and into which liquid is permitted to flow from the tank, when the liquid in the tank reaches a certain level, creating a liquid buffer in the chamber opposing movement of 70 the piston.

Another feature of our present invention consists in providing means creating a liquid buffer opposing the lower portion of the discharge stroke of the piston so as to prevent the piston striking against the bottom of the pump chamber. We accomplish this by providing means cutting off the discharge port of the pump chamber before the piston reaches the end of its discharge stroke so as 75 to trap a quantity of liquid in the pump chamber forming a liquid buffer opposing movement of the piston at the end of its discharge stroke.

Another feature of our invention consists 80 in means for overcoming the effect of the inertia of the column of liquid between the supply tank and the pump so as to render the pump more sensitive and the flow through it more nearly continuous. We accomplish this 85 by providing an intake chamber adjacent the inlet valve of the pump chamber and connected with the pump chamber through said valve, said intake chamber being connected by a suitable conduit with an external source 90 of supply and serving to maintain a quantity of liquid adjacent the inlet valve during the discharge stroke of the piston. Another feature of our present invention consists in making the weight separate from the piston and 95 connecting it to the piston so that the two move as one. In this case, the weight is connected to the piston so as to have a slight pivotal movement with respect to it, due to the pin connecting the annular or cup-shaped 100 weight and the piston and extending through slots in the wall of the cylinder in which the piston works. This is of advantage from a manufacturing standpoint since the piston and the stem, which is carried by the weight 105 and slidably mounted in the cover or top of the tank, do not have to be in exact axial alignment when this construction is employed.

The details of the construction of the 110 pumping tank are shown in Figure II in which 9 represents a tank which may be of pressed metal the bottom 10 of which is integral with the side. A separate top 11 is provided this being also preferably made of 115 pressed metal and this is fastened on the outwardly bent flanges 12 of the sides of the tank by screws 13 to hold the top in place. The cap 11 has a small opening 17 serving as a 120 vent to keep the inside of the tank at atmospheric pressure at all times.

The bottom of the tank has a screw threaded opening 18 at one side thereof into which a joint 19 is adapted to be screwed. One end 125 of this joint is adapted for connection with

the feed pipe to the carburetor of the engine or to the point of delivery of the liquid and the other end is designed to project up into the inside of the pump tank a slight distance above the bottom of the tank to provide a weir 5 so that liquid fuel inside the pump tank may flow to the carburetor or point of delivery when needed and yet the sediment settling at the extreme bottom of the tank will not flow 10 to the carburetor. At another place in the bottom of the tank a screw plug 20 is provided adapted to be removed for the draining of the tank or the removal of settled sediment therefrom.

15 The pumping mechanism of the pump tank consists primarily of a cylinder rigidly secured to and movable with the tank proper and a piston working therein cooperating with the cylinder to perform the pumping 20 operation. The cylinder we have shown in the drawing as having been made of cast material and it is indicated at 21. This cylinder is provided with flange 22 adapted to rest upon the upper edge of upwardly bent flange 23 of the bottom of the tank. The lower end 25 of this cylinder projects at 24 below the outside of the bottom of the tank and is there threaded to receive the threaded nut and nipple 25 the tightening of which serves to hold the flanges 22 and 23 together to maintain the cylinder firmly in place in the bottom of the tank inside the flange 23. The nut 25 is screw threaded at 26 for suitable connection with the feed pipe from the rear supply tank.

30 Slightly above the flange 22 of the cylinder 21 there is provided a transverse partition 27 which may be cast integrally with the cylinder, which partition forms a chamber 29 in the space beneath the same and above the lower end of the cylinder. The partition is 35 provided with a plurality of openings 28 connecting the chamber 29 therebeneath with the chamber above for a purpose to be hereinafter described. Upon the upper surface of this section 27 is adapted to fit a flat and light valve 29' of such diameter as to cover the upper ends of the openings 28 when the valve is seated. This valve is centered by projection 30 on its under side adapted to fit in a corresponding opening in the member 27. Just above the valve is a screw threaded plug 31 provided with openings 32 near its periphery and outside the periphery of the valve 29'. By this construction liquid is allowed to pass 40 upwardly through holes 28 around the edge of valve 29' and up through holes 32 to the pump chamber 33 but is prevented from flowing in the opposite direction as by doing so the valve would automatically lower to close the upper ends of the openings 28.

45 From the screw plug 31 upwardly the cylinder is preferably of the same diameter throughout but is closed however at its upper end by a cap 34 pressed or spun into place to 50 cover the upper end of the cylinder after the piston hereinafter described is placed in the cylinder through the upper end. The cylinder above the valve 29' is provided with longitudinal slots 35 the purpose of which will hereinafter appear. The cylinder is furthermore provided above these slots with other slots 36 through which a diametric pin 37 may pass for connecting the piston 38 with a weight 39 adapted to fit over the cylinder in a fairly close fit over the portion 34 of the cylinder cap. In assembling these parts, the piston 38, which is provided with a suitable opening to receive loosely the pin 37, is placed within the cylinder 21, the weight 39 is placed over the end of the cylinder, the pin 37 is inserted through suitable openings in the weight 39, through the slots 36 in the cylinder and through said opening in the piston 38, and the pin is secured in the weight 39, thus providing 55 a pivotal connection between the weight 39 and the piston 38.

60 A spring 40 of coiled formation has its lower end supported and guided by the flange 23 and surrounds the cylinder 21. The upper end of the spring 40 bears against the lower end of the weight 39 the spring being held in place at its upper end by a ring 41 formed by recessing the lower end of the weight 39. This spring serves to support the weight 39 which is longitudinally fixed with respect to the piston and supports the piston at a point of balance, from which point however, the piston and weight may move relatively upwardly or downwardly with respect to the cylinder. The piston 38 is adapted to fit the interior of the cylinder and it is provided with a counterbored portion 42 at its lower end into which screws a nut 43 provided with a ring of vertical openings 44. A light flat valve 45 is guided by a small projection on its under side which fits in the recess in the upper portion of the nut so as to cover the upper ends of the openings when the valve is lowered on its seat. From the recess around the valve 45 project holes 46 arranged in the form of a circle of greater diameter than the periphery of the valve 45 and these holes 46 open into transverse holes 47 which cooperate with the longitudinal slots 35 to allow liquid to flow from the pump chamber 33 past the valve 45 and through the openings just described and slots 35 into the exterior of the cylinder to fill the space 48 of the pump tank. This valve however will prevent 70 flow in the opposite direction through it.

75 The weight 39 as stated has a loose fit around the cylinder at all places except at the cap 34 and this weight is provided with relatively large openings 49 at its top connecting the top of the weight with the inside to allow any liquid that would get in the inside to be readily forced out of the space 50 as the piston and weight descend. Any liquid 80 inside the weight 39 below the part 34 will

freely flow downwardly between the lower portion of the weight and the cylinder into the liquid receiving portion of the tank.

The cap 34 for the cylinder is provided with an opening 51 in its top of quite small area and we may also provide openings 52 leading at an angle longitudinally through the piston from its upper end into communication with the slots in the cylinder in which the pin 37 slides. Either or both of these openings may be used but they are to be of such small cross section that should the liquid rise in the tank 48 to a level with the space 53 in the upper end of the cylinder liquid will flow through these holes into the space 53 and then if the piston is moved up relative to the cylinder the incompressible liquid in the space 53 would form a liquid buffer tending to dampen the movement of the piston and thereby materially reduce if not stop the pumping operation. The pumping however would normally be resumed when the liquid in the space 48 falls and allows the liquid in the space 53 to drain therefrom through openings 52 or to be forced gradually upwardly through opening 51 in the cap for the cylinder.

The cap 11 has a boss 14 through which passes an opening 15 serving as a guide and opening for an operating pin 16 connected with a member movable with the piston 38.

The operating handle 16 may be screw threaded or in any other way connected with the weight 39 so that if the part 16 is moved upwardly and downwardly manually or by the lifting up of the lever 54 on the dash which causes the end 55 of the same to press down on the rod 16 the pump will be manually operated.

In order to make smoother the flowing of liquid to the pump chamber from the rear tank and to minimize as far as possible any effect of inertia of the column of liquid and the work required for the starting and stopping of the intermittent motion of this column of liquid we provide a tube 56 the upper end of which is fastened in place in a depression 57 on the under side of the partition 27. This tube 56 forms a continuation of the opening leading from the rear supply tank to the pump chamber 33. It is not however entirely continuous with the opening 58 in the nut 25 as a slight space 59 is provided for connecting the opening 59 and 56 with a space 60 around the tube 56 and inside the lower end of the cylinder. Normally if the liquid were running through the pipe from the rear pipe to the pump continuously at the same speed the space 60 would have no material effect. Considering however that when the pump is started in operation there would be air in the space 60 then as liquid was being drawn into the pump space the air would also have been drawn out of the space 60 due to the inertia of the column of liquid

and before the same entered the pump reducing the pressure in space 60. Consequently when the column of liquid from the rear tank was in motion and reached the pump chamber some of it due to the slight vacuum in the space 60 would flow into the space at the lower part while the main column of liquid would continue to flow into the pump tank space 33. When the upward flow into the space 33 stopped however the column of liquid would tend to continue due to its inertia and the inertia of the column would tend to cause some of the liquid to flow into the space 60 and increase the pressure of the air in the upper space of the same. By the time the piston of the pump has completed its movement in a downward direction and starts back up again the cushion of air 60 above the liquid in the bottom of this space would then be under slightly more than atmospheric pressure and would tend to force the liquid through tube 56 and the valve into the pump cylinder more quickly than the liquid would flow if the column of gas all the way to the rear tank had again to be set in motion. This auxiliary space 60 therefore serves as a means of promoting more continuous flow of liquid from the rear tank through its pipes to the pump than would result without some provision for thus defeating the effects of the inertia of the column. By utilizing a means similar to this with a light valve we are able to have our pump function much more efficiently for the more sensitive or delicate vibrations.

To act as additional damper against extreme vibrations of the piston we arrange the transverse openings 47 in the piston at such a location that they will come below the extreme bottom end of the slots 35 before the bottom end of the piston will otherwise have reached the end of its down stroke. By doing this any undue downward movement of the piston is very effectively damped for the reason that liquid from the pump chamber 33 will no longer readily flow past the valve and through the opening 47 after this opening passes below the lower edge of slot 35 and is therefore closed by the wall of the cylinder. A slight leakage of the parts will prevent too sudden a stopping of the piston when it reaches a position to close the outlet 47 and by adjusting the fit of these parts the suddenness of the dampening may be controlled. By arranging the relative location of these slots and openings the maximum downward vibration of the piston may be definitely determined. As stated above the dampening of the piston in the opposite direction is controlled by the cover 34 for the cylinder and is effective when the liquid in the tank is sufficiently high as to be in the space 53 above the piston. When this is the case the upward movement of the piston is damped and

with a suddenness determined by the size of the apertures 51 and 52 through which the liquid must flow out if the piston is to displace the same.

5 It will appear from the above that any oscillation of the tank 9 in a vertical direction whether caused by the vibration of the car when running or the engine or whether positively vibrated by some other means 10 will due to the inertia of the piston 38 and weight 39 result in relative movement between the piston 38 and weight 39 and the tank 9 and relatively fixed cylinder 21. This 15 results in successive increasing and decreasing of the space 33 with the result that liquid is pumped from the rear tank into the space 33 and then forced out of the same through the openings in the piston and slots 35 into the space 48 of the tank. Any 20 extreme vibrations of the piston relative to the cylinder are controlled by the downward dampening movement of the piston as controlled by the location of slots 35 and openings 47 and any extreme upward dampening is controlled by the dampening chamber 53 above the upper end of the piston. The height of the liquid in the tank space 25 48 is kept fairly constant as when the liquid rises to a sufficient height it will fill the space 53 above the piston and diminish further vibration of the same until the level of the liquid again lowers and this space is drained of the liquid. The pumping will then again be resumed as the vibration of the tank continues.

The provision of the space 60 around the entrance pipe 56 in the cylinder serves to tend to keep a more continuous flow of the liquid through the supply pipe from the 40 rear tank and thus make the operation of the mechanism more sensitive and effective than would otherwise be the case if the pump had to overcome the inertia of a still body of liquid when it resumes its sucking operation rather than merely increase the movement of the still moving column.

While the device is shown as being operated by the vibration of the automobile when in use or when the engine is running, 50 if it is desired to vibrate the pump cylinder and casing positively the same may be readily accomplished by mounting the pump slidably on its support and through cam and rod or lever connections positively operating the same to vibrate it from a cam on some moving part of the engine or vehicle.

We are aware that the pumping apparatus and the fuel feed system disclosed in 60 this specification and the accompanying drawing may be altered, changed or varied considerably without departing from the spirit of our invention and, therefore, we claim our invention broadly, as indicated by 65 the appended claims.

Having thus described our invention what we claim is:

1. A device of the class described comprising a receiving tank; a pump operated by inertia and discharging into said tank; and means, automatically initiated by the level of the liquid in said tank, for opposing a variable resistance to the intake stroke of the pump.

2. In a fuel supply system for automotive vehicles, the combination of a receiving tank mounted on the vehicle; a pump discharging into said tank and operated automatically by the vibrations normally inherent in the automotive vehicle when in operation, said pump including a piston; and means, controlled by the level of the liquid in the tank, for creating a liquid buffer opposing the intake stroke of the piston, and a separate liquid buffer opposing the outlet stroke thereof.

3. A device of the class described comprising a receiving tank; a pump discharging into said tank and including a pump chamber and a resiliently supported piston reciprocating in said chamber; and means, controlled by the level of the liquid in said tank, for creating a liquid buffer opposing the intake stroke of said piston and a separate liquid buffer opposing the outlet stroke thereof.

4. A device of the class described comprising a receiving tank; a pump discharging into said tank and including a pump chamber adapted to be connected to an external source of supply and a resiliently supported piston reciprocating in said chamber; said piston having a discharge port therein; a valve controlling said discharge port; a buffer chamber in which said piston also reciprocates; means, controlled by the level of the liquid in said tank, for admitting liquid to said buffer chamber to create a liquid buffer opposing movement of the piston; and additional means also controlled by the level of the liquid in said tank for further opposing movement of the piston.

5. A device of the class described comprising a receiving tank; a cylinder having an inlet at one end and a restricted outlet at the other end; a piston reciprocating in said cylinder and dividing it into a pump chamber and a buffer chamber; means for discharging liquid from said pump chamber into said tank; means, controlled by the level of the liquid in the tank, for admitting liquid to said buffer chamber to create a liquid buffer opposing movement of the piston; and additional means also controlled by the level of the liquid in the tank for further opposing movement of the piston.

6. A device of the class described comprising a receiving tank; a cylinder rigidly mounted within the tank and having an inlet at one end, adapted to be connected to an external source of supply, and a restricted out-

let at the other end; a piston reciprocating in the cylinder and dividing it into a pump chamber and a buffer chamber; a weight surrounding the cylinder and connected to move with the piston; means for discharging liquid from the pump chamber into the tank; a port connecting the buffer chamber with the interior of the tank, whereby when the liquid reaches a predetermined level in the tank, it enters the buffer chamber creating a liquid buffer therein opposing movement of the piston.

7. A device of the class described comprising a receiving tank; a cylinder rigidly mounted within the tank and having an inlet at one end, adapted to be connected to an external source of supply, and a restricted outlet at the other end; a piston reciprocating in the cylinder and dividing it into a pump chamber and a buffer chamber; a weight surrounding the cylinder and connected to the piston to move therewith and forming an additional buffer chamber with the upper end of the cylinder; a coil spring surrounding the cylinder and supporting the weight; means for discharging liquid from the pump chamber into the tank; a port connecting the buffer chamber and the interior of the tank, whereby, when the liquid reaches a predetermined level in the tank, it enters the buffer chamber creating a liquid buffer therein opposing movement of the piston; and a port connecting said first buffer chamber with said additional buffer chamber whereby liquid may also enter said additional buffer chamber and create a liquid buffer additionally opposing movement of said piston.

8. A device of the class described comprising a receiving tank; a cylinder rigidly mounted within the tank and having an inlet at one end, adapted to be connected to an external source of supply, and a restricted outlet at the other end; said cylinder having a pair of diametrically opposite slots in the wall thereof; a piston reciprocating in the cylinder and dividing it into a pump chamber and a buffer chamber; a resiliently supported weight surrounding the cylinder; a pin carried by said weight and extending through said slots and through the piston; means for discharging liquid from the pump chamber into the tank; a port connecting the buffer chamber with the interior of the tank, whereby, when the liquid reaches a predetermined level in the tank, it enters the buffer chamber creating a liquid buffer opposing movement of the piston; and means associated with said weight for creating an additional liquid buffer opposing movement of said piston.

9. A device of the class described comprising a receiving tank; a cylinder mounted within the tank and having an inlet at one

end, adapted to be connected to an external source of supply, and a restricted outlet at the other end; a piston reciprocating in said cylinder and dividing it into a pump chamber and a buffer chamber; a resiliently supported, cup-shaped weight surrounding the upper end of the cylinder and connected to the piston to move therewith; means for discharging liquid from the pump chamber into the tank; and a port connecting the buffer chamber and the interior of the tank whereby, when the liquid in the tank reaches a predetermined level, it enters the buffer chamber creating a liquid buffer therein opposing movement of the piston.

10. A device of the class described comprising a receiving tank; a pump chamber therein having an inlet adapted to be connected to an external source of supply; a piston reciprocating in said chamber; a resiliently supported weight pivotally connected to said piston; and means for discharging liquid from said pump chamber into the tank.

11. A device of the class described comprising a receiving tank; a pump chamber therein having an inlet adapted to be connected to an external source of supply; a piston reciprocating in said chamber; a resiliently supported weight pivotally connected to said piston; a stem carried by said weight and slidably mounted in the top of the tank; and means for discharging liquid from said pump chamber into said tank.

12. A device of the class described comprising a receiving tank; a pump chamber therein having an inlet adapted to be connected to an external source of supply; a piston reciprocating in said chamber; a resiliently supported weight pivotally connected to said piston; means for discharging liquid from the pump chamber into said tank; a buffer chamber in which a part moving with the piston works; and means, controlled by the level of the liquid in the tank, for admitting liquid to said buffer chamber to create a liquid buffer therein opposing movement of the piston.

13. A device of the class described comprising a receiving tank; a cylinder mounted within the tank and having an inlet at its lower end, adapted to be connected to an external source of supply, and a restricted outlet at the upper end; a piston reciprocating in the cylinder and dividing it into a lower pump chamber and an upper buffer chamber; a resiliently supported weight surrounding the upper portion of the cylinder but spaced therefrom to permit liquid to flow to the buffer chamber; said weight being connected to the piston to move therewith; means for discharging liquid from the pump chamber into the tank; and a port connecting said buffer chamber and the interior of the tank, whereby, when the liquid reaches a predetermined

level in the tank, it enters the buffer chamber creating a liquid buffer opposing movement of the piston.

14. A device of the class described comprising a receiving tank; a pump chamber discharging into said tank; an inertia-operated piston reciprocating in said chamber; and means creating a liquid buffer opposing the discharge stroke of the piston, said means being operative independently of the level of the liquid in the tank and a reserve chamber adjacent said pump chamber for supplying liquid to the pump chamber.

15. In a liquid feed system, the combination of a casing, a pump positioned within the casing for supplying liquid thereto, and means for damping movement of said pump when the supply of liquid exceeds a given level, said pump comprising a cylinder, a piston movable within the cylinder, and said damping means comprising a chamber within, said cylinder at the outer end of said piston and having a permanently unobstructed aperture in its wall and a second chamber outside of said cylinder and communicating with said first chamber, and means to vary the volume of said second chamber with the movement of said piston.

In testimony whereof, we affix our signatures.

CHESTER H. BRASELTON.
